UNITED STATES PATENT OFFICE

RICHARD H. JORDAN, OF SPRINGFIELD, MASSACHUSETTS, DONALD L. HADLEY, OF MANSFIELD, OHIO, AND DONALD R. DOHNER, OF PITTSBURGH, PENNSYLVANIA, AS- SIGNORS TO WESTINGHOUSE ELECTRIC AND MANUFACTURING COMPANY, A COR- PORATION OF PENNSYLVANIA

DESIGN FOR A MOTOR DRIVEN FAN

Application filed March 27, 1931. Serial No. 39,273. Term of patent 7 years.

To all whom it may concern:

Be it known that we, RICHARD H. JORDAN, a citizen of Germany, residing at Springfield, in the county of Hampden and State of Massachusetts, DONALD L. HADLEY, a citizen of the United States and a resident of Mansfield, in the county of Richland and the State of Ohio, and DONALD R. DOHNER, a citizen of the United States and a resident of Pittsburgh, in the county of Allegheny and the State of Pennsylvania, have invented a new, original, and ornamental Design for a Motor Driven Fan, of which the following is a specification, reference being had to the accom-

panying drawings, constituting a part hereof.

Figure 1 is a view, in front elevation, of our new design for a motor driven fan,

Fig. 2 is a view, in side elevation, thereof.

We claim:—

The ornamental design for a motor driven fan as shown.

In testimony whereof, we have hereunto subscribed our names.

RICHARD H. JORDAN.
DONALD L. HADLEY.
DONALD R. DOHNER.
